CHAIN SAW

Raymond C. Whitlock, San Francisco, Calif.

Application September 14, 1944, Serial No. 553,965

1 Claim. (Cl. 143—32)

1

This invention relates to improvements in saws and has particular reference to the construction of a chain saw, wherein an unique arrangement of replaceable cutting blades is employed to readily accomplish varying degrees of thickness in cuts in the felling of trees and like articles to be sawed.

A further object of the invention is the provision of novel motor driven means for effectively actuating the saw and thus providing an efficient labor saving apparatus that will accomplish the cutting operation in a minimum amount of time.

An additional object of the invention is the provision of pressure plates associated with the driving motor, whereby danger of slippage of the saw will be eliminated when the cutting operation is being performed and which pressure plates function to direct the saw to its cutting position.

A further object of the invention is the provision of tensioning means in the form of a cable which has associated therewith turn-buckles to take up slack in the body of the saw.

An additional object of the invention is the provision of a chain saw of the character described that is positive in operation, economical to manufacture, strong and durable.

Other objects and advantages will be apparent during the course of the following description.

In the accompanying drawings wherein for the purpose of illustration is shown the preferred embodiment of the invention,

Fig. 1 is a top plan view of the chain saw constructed in accordance with my invention,

Fig. 2 is a side elevational view and partly in section, on an enlarged scale of the motor, the bracket supported by the motor and likewise illustrating the segmental pressure plates and associated mechanism for eliminating danger of slippage of the saw teeth, the view being taken on the line 2—2 of Fig. 1,

Fig. 3 is a transverse sectional view through the casing disclosing the grooved pulley and associated mechanism, the view being taken on the line 3—3 of Fig. 1,

Fig. 4 is a fragmentary top plan view of the saw blades.

Fig. 5 is a front elevation of the same, and

Fig. 6 is a vertical section through the blades and mounting thereof, the view being taken on the line 6—6 of Fig. 5.

In the accompanying drawing the numeral 1 indicates a semi-circular shield or casing that is secured as at 8 to the body 9. This shield is grasped by the operator in manipulating the saw. To said body apertured lugs 10 and 11 are secured

5 that receive therein a pin 12 on which rollers 13, positioned between spacers 14, rotate. As disclosed to advantage in Fig. 3 it will be noted that the inner edge of the chain saw, indicated as a whole by the reference character A, passes freely over the outer peripheries of the rollers 13. The said spacers serve to guide the chain saw in its continuous endless movement and likewise function to retain said rollers therebetween for freedom of rotary movement on the pins 12.

10 Supported on the respective ends B and C of the shields is the medium for driving the chain saw, which medium comprises an air motor 14. It is obvious that one or two motors may be employed and since the said motor and associated mechanisms are similar in construction, but one motor and one distinctive mechanism will be described.

15 The preferred motor utilized is of the air type, as stated, and is employed because of its lightness in weight and its effectiveness in driving the chain saw. A band 15 encircles and is secured to the motor housing and has suitably connected thereto a bracket 16 equipped with an arm 17 on which is suspended a stationary yoke 18 that has rotatably mounted thereon a roller 19 in frictional contact with one of a plurality of segmental pressure plates 20. The nature and construction and the preferred number of said plates are disclosed to advantage in Fig. 1 and on an enlarged scale in Fig. 2 of the drawing.

20 It will be noted as illustrated that the motor shaft 21 of the motor 14 has keyed thereto for rotation with said shaft, a circular plate or disc 22 that is reduced in thickness adjacent its marginal edges. The upper end of the shaft is threaded to receive thereon the internal threads of an enlarged hexagonal nut 23 to the faces of which are secured lugs 24 to which the said pressure plates are pivoted as at 25. Tension springs 26 are interposed between the lower faces of said pressure plates and the reduced body of the disc 22 which reduced body is preferably insulated to eliminate excessive wear thereon. Likewise lock nuts 28 are employed to obtain a proper tensioning of the springs, and after the pressure point is passed the spring frees the pressure plate from the chain saw. It will be obvious that as each segmental pressure plate passes beneath the roller 18 in the course of travel of the chain saw, pressure will be exerted on the contacted saw blade or mounting thereof, while the remaining pressure plates will assume the normal position illustrated in Fig. 2 on the right hand side of said figure.

A cable 30, equipped with turn-buckles 31, is secured to the end of the frame adjacent the motor housing. By manipulating the turn-buckles any slack in the frame can be compensated for. The cable is retained in position by contact with staggered lugs carried by the frame.

The chain saw per se consists of a plurality of interconnected blade mountings 32 and 33. The mounting 33 has riveted or otherwise secured between the side walls thereof the preferred type of cutter blade 35. I propose to employ that will most effectively perform the cutting or sawing operation. The mounting 32 has associated therewith pairs of cleanout or drag blades 34 that function to remove accumulated matter from the cut. The respective mountings are pivoted one to the other and a steel bearing 36 is employed at the pivotal point to provide a sturdy construction. It is obvious that varying types of blades may be utilized and in the present invention these blades may be conveniently replaced after the desired usage of the same.

From the foregoing description considered in connection with the accompanying drawings it will be obvious that I have produced a most efficient chain saw and driving mechanism therefor that will be effective in a great saving of labor in producing the desired results.

It is to be understood that the form of the invention herewith shown and described is to be taken as a preferred example of the same and that various changes relative to the shape, size, material, and arrangement of parts may be resorted to without departing from the spirit of the invention or the scope of the subjoined claim.

Having thus described my invention, I claim:
In a saw apparatus, a shield, an endless cut-

ter chain mounted in said shield and adapted to contact a tree to be felled, means for guiding said cutter chain in said shield, turntables positioned at each end of said shield, means for motivating said turntables, said means comprising motor driven shafts connected to said turntables, means connected to the motors for supporting rollers, and segmental pressure plates secured to said motor shafts and positioned above said turntables and capable of being depressed under the influence of the rollers to force portions of said cutter chains into engagement with said turntables, said means for securing said pressure plates to said shafts comprising a nut threadedly engaging the upper end of each of said shafts, and a lug formed on each face of each of said nuts forming a pivotal mounting for each of said pressure plates.

RAYMOND C. WHITLOCK.
